UNITED STATES PATENT OFFICE.

WILLIAM J. HATFIELD, OF BUFFALO, NEW YORK, ASSIGNOR OF ONE-HALF
TO HENRY A. MILLER, OF SAME PLACE.

KNIT MITTEN.

SPECIFICATION forming part of Letters Patent No. 245,066, dated August 2, 1881.

Application filed April 19, 1881. (No model.)

To all whom it may concern:

Be it known that I, WILLIAM J. HATFIELD, of the city of Buffalo, in the county of Erie and State of New York, have invented new 5 and useful Improvements in Knit Mittens, of which the following is a specification, reference being had to the accompanying drawings.

This invention relates more particularly to the manufacture of mittens composed of two 10 thicknesses or webs, and it has for its object to produce such mittens in a more expeditious manner than heretofore.

My invention consists of the particular construction of the hand portion and the thumb 15 of the mitten, as hereinafter fully set forth.

In the accompanying drawings, Figure 1 is a view of my improved mitten. Fig. 2 is a view of the blank of the hand portion before it is folded. Fig. 3 is a view of the blank of 20 the thumb before it is folded. Fig. 4 is a view of the blank of the hand portion folded and sewed. Fig. 5 is a view of the blank of the thumb portion folded and sewed.

Like letters of reference refer to like parts 25 in the several figures.

A represents the blank of the hand portion. This blank is formed of a circular web which is closed at *a* at the end of the wristband, where the web is commenced in knitting and 30 open at the opposite end, as shown at *b*. The blank is made twice as wide as the mitten for which it is intended, so that it will form a mitten of the desired size when folded lengthwise.

C represents the blank of the thumb, which 35 is formed of a circular web, which is closed at *d*, where it is commenced and open at *e*. This blank is also made twice as wide as the thumb for which it is intended, so that it will form a thumb of the required size by folding the blank 40 lengthwise. The blank A for the hand portion is now folded lengthwise, and its two longitudinal edges are sewed together with the exception of the place where the thumb is to be joined to the blank, which is left open to 45 form the thumb-slit *f*. The thumb-blank C is also folded lengthwise, and its two longitudinal edges are sewed together with the exception of the tapering portion *g*, which is to be

connected with the hand-blank around the thumb-slit *f*. The thumb is then attached to 50 the hand-blank by sewing the edges of its open tapering end to the hand-blank along the edges of the thumb-slit *f*, and the open ends *b* and *e* of the hand portion and the thumb are closed by sewing, whereby the mitten is completed. 55

The adjoining longitudinal edges of the hand-blank and of the thumb-blank are formed by the ordinary web of the blanks and not by selvage, whereby a smooth, soft joint or seam is produced. 60

The circular web is produced in about the same time in which a flat web of half the width is produced, and a mitten of double thickness is thereby produced as rapidly as an ordinary mitten of single thickness. As the circular 65 web of the hand portion is commenced at the edge of the wristband, the circular web is closed along the edge of the wristband, whereby a seam at that edge is avoided.

I claim as my invention— 70

1. The method of forming a hand portion, A, of double thickness, which consists in first knitting a circular web closed at the edge of the wristband, then folding the web lengthwise and sewing the edges of the web together, with 75 the exception of the thumb-opening, substantially as set forth.

2. The method of forming the thumb C of double thickness, which consists in first knitting a circular web of the required shape, then 80 folding the web lengthwise and sewing the edges together, with the exception of those portions which are to be sewed to the hand portion, substantially as set forth.

3. A knit mitten of double thickness, consisting of a hand portion, A, and thumb C, each composed of a circular web folded lengthwise, and having its edges sewed together, except around the thumb-opening, where the edges of the thumb portion are sewed to the edges of 90 the web of the hand portion, substantially as set forth.

WILLIAM J. HATFIELD.
